(57) CLAIM

The ornamental design for a belt, as shown and described.

DESCRIPTION

FIG. 1 is a perspective view of a belt showing my new design, the belt shown being worn by a human being in dotted lines which forms no part of the invention;

FIG. 2 is a front view thereof;

FIG. 3 is a top view thereof; the opposite view being a mirror image thereof;

FIG. 4 is a right view thereof;

FIG. 5 is a left view thereof; and,

FIG. 6 is a rear view thereof.
